UNITED STATES PATENT OFFICE.

LEE WOODWARD ZEIGLER, OF NEW WINDSOR, NEWBURGH, NEW YORK.

DESIGN FOR A STATUE.

Application filed March 21, 1923. Serial No. 5,552. Term of patent 3½ years.

To all whom it may concern:

Be it known that I, LEE WOODWARD ZEIGLER, a citizen of the United States, and a resident of New Windsor, Newburgh, in the county of Orange and State of New York, have invented a new, original, and ornamental Design for a Statue, of which the following is a specification, reference being had to the accompanying drawing, forming part thereof.

The figure is a front elevation of a statue, showing my new design.

I claim:

The ornamental design for a statue, as shown.

LEE WOODWARD ZEIGLER.
